(57) **CLAIM**

The ornamental design for a fit connector member, as shown and described.

DESCRIPTION

FIG. 1 is a front elevational view of a fit connector member showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a partial, enlarged view showing the fit connector member defined by lines 7—7 of FIG. 1;

FIG. 8 is a partial, enlarged view showing the fit connector member defined by lines 8—8 of FIG. 2;

FIG. 9 is a cross-sectional view showing the fit connector member along lines 9—9 of FIG. 5;

FIG. 10 is a cross-sectional view showing the fit connector member along lines 10—10 of FIG. 5;

FIG. 11 is a partial, enlarged view showing the fit connector member defined by lines 11—11 of FIG. 6;

FIG. 12 is a front, bottom and right side perspective view thereof; and,

FIG. 13 is a rear, top and right side perspective view thereof.
